ARTICULATED VIBRATORY ROLLER

John T. Carnahan, Fairborn, Ohio, assignor to
Koehring Company, Milwaukee, Wis.

Filed Dec. 13, 1971, Ser. No. 207,702

Term of patent 14 years

Int. Cl. D12—09

U.S. Cl. D40—5 R

FIG-1

FIG-2

FIG-3

FIG-4

FIG. 1 is a perspective view of an articulated vibratory roller embodying my new design;

FIG. 2 is a side elevational view thereof;

FIG. 3 is a rear elevational view thereof; and

FIG. 4 is a top plan view thereof with cables being omitted for ease of illustration.

I claim:

The ornamental design for an articulated vibratory roller, substantially as shown and described.
